(57) **CLAIM**

The ornamental design for a decorative light, as shown and described.

DESCRIPTION

The nature and intended use of the article in which the design is embodied is that of an electrically operated light that may be used for decorative purposes, such as for providing light at parties and the like. Rays of light are reflected outwards from the light omnidirectionally.

FIG. 1 is a perspective view of a decorative light showing my new design;

FIG. 2 is a top view thereof;

FIG. 3 is a bottom view thereof;

FIG. 4 is a front elevational view thereof;

FIG. 5 is a rear elevational view thereof;

FIG. 6 is a left side view thereof; and,

FIG. 7 is a right side view thereof.

1 Claim, 6 Drawing Sheets
